UNITED STATES PATENT OFFICE.

WILLIAM TOPP AND FRANK TOPP, OF GRANBY, QUEBEC, CANADA.

AUTOMATIC FIRE-ALARM.

1,057,784.

Specification of Letters Patent.

Patented Apr. 1, 1913.

Application filed February 8, 1911. Serial No. 607,335.

To all whom it may concern:

Be it known that we, WILLIAM TOPP and FRANK TOPP, both subjects of the King of Great Britain, and residents of the town 5 of Granby, in the Province of Quebec, in the Dominion of Canada, have invented certain new and useful Improvements in Automatic Fire-Alarms; and we do hereby declare that the following is a full, clear, and 10 exact description of the same.

The invention relates to improvements in automatic fire alarms, as described in the present specification and illustrated in the accompanying drawings that form part of 15 the same.

The invention consists essentially in the novel device and wiring employed to sound alarms on an abnormal increase of temperature in proximity to said device.

20 The objects of the invention are to save the destruction of property and lives from fire, to devise a simple arrangement of parts in automatic alarms, and generally to provide an efficient system for notifying occupants of hotels, factories and other places 25 of the presence of a fire in any one part.

In the drawings, Figure 1 is a perspective detail of a switch member. Fig. 2 is a diagrammatic view of the wiring, showing the 30 switches and translating devices.

Like numerals of reference indicate corresponding parts in each figure.

Referring to the drawings, 1 is the base of 35 a switch member, formed of suitable insulating material having the plate contacts 2 and 3 set therein at one end and thumb screws 4 and 5 turning on correspondingly threaded pins 6 and 7 projecting upwardly from said contacts 2 and 3.

40 8 is a spring contact having the forked end 9 sprung into contact with the plates 2 and 3 and projecting from the plate 10, the latter being set in the base 1 at the opposite end to the plates 2 and 3.

45 11 is a thumb screw turning on the correspondingly threaded pin 12, the latter projecting upwardly from the plate 10.

13 is a pin or post of fusible material, 50 preferably a fusible metal and introduced between the base 1 and the underside of the spring contact 8 and of sufficient strength to normally counteract the spring of said contact 8 and hold said forked end 9 from engagement with the contacts 2 and 3. It 55 will be thus seen that on sufficient increase of the temperature in proximity to the pin

13, the said pin will melt and thus permit the forked end 9 to engage the contacts 2 and 3 and the result of this will be understood from the following explanation in regard to the wiring and the alarms. 60

A, B and C are switch members of the type described hereinbefore.

15 and 16 are alarm bells.

17 is an electric battery. 65

18 is a lead wire from the battery through the alarm bells 15 and 16 and the switch members C and B to the contact plate 3 of the switch member A, therefore, there is a through connection from the contact plate 3 70 of the switch member A including the switch members B and C and the bells 15 and 16 to the battery 17.

19 is a lead wire from the battery 17, through the switches A, B and C connecting 75 said battery with the contact plates 2 of said switches respectively and terminating at the contact plate 2 of the switch C, therefore, it will be noted that the electric bridging of any one of the plates 2 with any one 80 of the plates 3 will close the circuit including said switches, said bells and said battery, consequently all the bells will ring.

The contacts 2 and 3 are respectively closed by a spring contact 8, the forked end 85 of said spring contact bridging the said plates 2 and 3 and in this way the switches A, B and C or as many more as may be required, keep the circuit open as long as the fusible pins 13 hold the spring contacts 8 in 90 their upper position.

Presuming this system is installed in a building used for hotel purposes, the switch members are placed in different parts of the building, in fact anywhere that there is a 95 chance at all of a fire gaining head-way. Very often this place would be in the furnace room or kitchens and consequently these parts will be particularly well equipped with the switch members, of course, 100 if it is advisable, said switch members can be installed in every room in the hotel, but perhaps that may not be necessary. The alarm bells, however, will be distributed throughout the building, particularly in the 105 sleeping rooms of the guests and employees and the executive and these will all be in the main wire from the battery running back through the switches and terminating at the first switch. The other lead wire, of course, establishes the connection through 110 any one of said switches and immediately

that connection is established, the bells ring all over the hotel and any sleeping guests will be at once awakened and have ample time to leave the building in safety.

5. What we claim as our invention is:

1. In an automatic fire alarm, a switch member comprising a base plate, a pair of contact plates lying on the surface of said base plate at one end thereof, a spring contact secured to said base at one end and bowed intermediately and terminating in a pair of inwardly extending pointed tines adapted to respectively contact said contact plate, a fusible prop between said bowed portion and the base plate normally holding said contact tines out of engagement with the plates, and terminal posts on said contact plates.

2. In an automatic fire alarm, a switch member comprising a base plate, a pair of

contact plates lying on the surface of said base plate at one end thereof, a spring contact secured to said base at one end and bowed intermediately and terminating in a downwardly extending bifurcated part 25 forming a pair of flaring tines adapted to respectively make rubbing contact at their points with said contact plates, a fusible prop between said bowed portion and the base plate normally holding said contact 30 tines out of engagement with the plates, and terminal posts on said contact plates.

Signed at the city and district of Montreal, Quebec, Canada, this second day of February, 1911.

WILLIAM TOPP.
FRANK TOPP.
